A. CRUICKSHANK

PLIER WRENCH

Filed July 9, 1924

Inventor
Alexander Cruickshank

By Albert B. Dietrich
Attorney

Patented Nov. 17, 1925.

UNITED STATES PATENT OFFICE.

ALEXANDER CRUICKSHANK, OF MATSQUI, BRITISH COLUMBIA, CANADA.

PLIER WRENCH.

Application filed July 9, 1924. Serial No. 724,993.

To all whom it may concern:

Be it known that I, ALEXANDER CRUICKSHANK, citizen of the Dominion of Canada, residing at Matsqui, in the Province of British Columbia, Canada, have invented certain new and useful Improvements in Plier Wrenches, of which the following is a specification.

This invention relates to a plier nut wrench having provision for obtaining a flat bearing of one of the jaws of the plier on a plane of the nut to which it is applied and for securing the jaws in the desired position of opening.

15 The invention is fully described in the following specification, reference being made to the drawings by which it is accompanied, in which:

Fig. 1 is a face view of the wrench complete.

Fig. 2, an edge view of one of the handled jaw members, being on the line 2—2 in Fig. 1.

Fig. 3 is a cross section to an enlarged scale on the line 3—3 in Fig. 1, and

Fig. 4 is a similar view of a modified form of pivotal connection.

20 In these drawings 2, 3; 4, 5 represent the opposed plier members which are pivotally connected together by a pin 6 having a customary provision for varying the jaw opening of the plier.

To one of the jaw members 3, adjacent its outer end, a member 7 is pivotally connected 35 at 8 to its inner side to have a limited rocking movement in relation to the acting face of that jaw. The member 7 may, as shown in Fig. 3, have a divided bearing on the jaw member, or, as shown in Fig. 4, may have its 40 bearing all on one side.

The pin 8 is relatively a loose fit in the member 7 and in the jaw to which it is connected to permit the outer edge of the pivotal eye of the member 7 to take its bearing 45 at 15 direct on the jaw, whereby the pin 8 is relieved of the strain, and a fuller area is afforded to endwise wear.

When this device is applied to a nut, instead of the jaw member 3 making contact 50 with the nut at one place, either adjacent the point or adjacent the pivot 6, according to the amount of opening of the wrench, the member 7 adapts itself to the plane of the nut and takes a uniform bearing thereon 55 whereby injury to the nut is avoided and a more effective hold is attached.

The pivoted member 7 may have a lengthwise V-groove 9 to enable a wire or pin to be effectively held.

A small handled lever 12 is pivotally 60 mounted at 10 on the inner side of one handle member 2 of the pliers adjacent the other handle member 4. The handled lever 12 has an eccentric portion 11 around the pivot 10, on which eccentric portion fits the 65 eye of a pawl 13 which engages any one of a series of notches 14 formed on the lever member 4 adjacent thereto.

If the eccentric 11 is turned to the position indicated by the dot and dash lines, the 70 pawl 13 is free to turn on the eccentric 11, and may be withdrawn from its engagement with the jaw member 5, but when the eccentric is turned to the position shown by full lines in Fig. 1, the strap of the pawl is 75 pressed against the handled jaw member 4, 5, the pawl is retained in the set position of retaining engagement by the wedging action of the eccentric against the handle member 4.

In use, the pliers are largely adjusted on their pin 6 to the size of the nut, and the ratchet pawl 13 is released to turn freely on its pin by movement of the eccentric extension 12 to the position shown by dot and dash lines. The pliers are then gripped in the hand to tightly close the jaws 3, 5 on the nut and by the thumb of the gripping hand the pawl 13 is then moved into engagement with one of the notches 14 and again 85 with the thumb the extension 12 is moved against the handle to tighten the eccentric and retain the pawl in the adjusted position.

The device forms a simple and inexpensive addition to an existing form of wrench 90 and renders its use more satisfactory in the manner explained.

Having now particularly described my invention, I hereby declare that what I claim as new and desire to be protected in by Letters Patent, is:

1. In a plier wrench, a flat faced member having arcuate bearing ears mounted in arcuate bearing recesses on the inner side of one of the jaws to have a limited rocking movement about an axis parallel to that of the hinge pin of the plier members, means holding said flat faced member in place, and means for securing the jaw members in an adjusted position against movement outward therefrom, said means comprising a pawl and ratchet connection between said

levers and a shiftable eccentric on which the pawl is mounted.

2. In a plier wrench having crossed handles pivoted together, means for holding the wrench closed on an object, said means comprising a pawl and ratchet device which includes a lever pivoted to one handle member and having an eccentric bearing portion and a pawl having an eye mounted on said eccentric bearing portion, said lever being mounted adjacent to the handle of the opposing plier member whereby when said lever is moved on its pivot to bring said pawl into engagement with the ratchet, the eccen-

tric will be moved toward the plier handle 15 into holding engagement therewith, substantially as shown and described.

3. A plier wrench comprising crossed levers pivoted together, a small lever pivotally mounted on one of the crossed levers 20 and having an eccentric around the pivot, and a pawl mounted on the eccentric of the small lever and adapted to engage notches on the other crossed lever, substantially as specified.

In testimony whereof I affix my signature.

ALEXANDER CRUICKSHANK.
